Atty's

UNITED STATES PATENT OFFICE.

ALEXANDER S. SPIEGEL, OF CHICAGO, ILLINOIS.

EXPANSION-JOINT FOR ROADS.

1,280,572.

Specification of Letters Patent.

Patented Oct. 1, 1918.

Application filed July 21, 1917. Serial No. 182,019.

To all whom it may concern:

Be it known that I, ALEXANDER S. SPIEGEL, a citizen of the United States, and resident of Chicago, Illinois, have invented certain new and useful Improvements in Expansion-Joints for Roads, of which the following is a specification.

My invention relates to what is known as an expandible joint for pavements to compensate for the contraction and expansion 10 of the material comprising a pavement and at the same time the invention aims to make such a joint as will prevent the passage of water beneath the road bed.

I aim in the present form of my invention to provide a joint which will not only be elastic but which will become integral with the material of the road to such an extent as neither heat nor cold will cause a separation 20 at the point of juncture.

In the accompanying drawing,

Figure 1 shows one form of my improved joint.

Fig. 2 shows a second form.

Fig. 3 shows a third form.

In carrying out my invention I use a compound 1, which consists of asphalt, saw-dust, spent tan bark or like ingredients having a certain degree of elasticity and as shown in Fig. 1 I use this as the body or center of the joint. I confine the elastic compound between two felt strips 2 saturated with asphalt which not only holds the central compound in place but adheres closely with it naturally. Upon the saturated felt I apply a coating of asphalt 3 of a high melting point and then I apply to this surface crushed stone. Thus I secure a roughened outer face which adheres readily to the face

40 of the road bed exposed to it not only forming a close connection but preventing displacement by reason of the roughened character of the outer face of the joint, due to the crushed stone and it will be observed 45 that while there is a close connection between the outer face of the joint and the adjacent face of the road I have provided between the confining walls of saturated felt an elastic body medium which permits con- 50 traction and expansion without permitting separation of the joint either as to its com-

ponent parts or in its connection with the adjacent road bed.

While I prefer the form shown in Fig. 1 I may, as shown in Fig. 2, use a central 55 strengthening strip of felt 2^a, Fig. 2, being in all other respects like Fig. 1.

An inferior type of joint may be made, as shown in Fig. 3, by omitting the outer confining walls of felt using simply the central 60 strip.

The advantages of my construction are as follows:

1. When the concrete road is laid the crushed stone surface or wall of the expansion joint will unite with the concrete and become an integral part of the road. 65

2. As in my joint the crushed stone is embedded into the coating, as in Fig. 1, and becomes a part of the road bed, the contraction or expansion of the road bed will simply expand or contract the elastic compound without actual separation of the joint. 70

3. The use of the coating also prevents the drying up of the felt, as the felt saturated as 75 it is with a very light and oily asphalt would soon evaporate unless protected by the coating.

What I claim is:—

1. In combination, concrete members, and an interposed joint filler of resilient material having surface layers of non-resilient material which are adhesively affixed to the resilient filler and bonded to the concrete members. 80

2. In combination, a concrete member, and a joint filler of resilient material having a surface layer of material which is adhesively affixed to the resilient material and is bonded to the concrete member. 85

3. An expansion joint strip comprising a body of compressible material, a layer of coarse granular material partially embedded in and adhering to the surface of said compressible material and adapted to bond with 90 plastic material cast in contact with said granular material.

4. An expansion joint for pavements or road beds comprising two surface coatings, crushed stone embedded therein and an 100 elastic compound between the coatings, substantially as described.

5. In an elastic joint for road beds, two confining walls of felt coated upon their outer faces, crushed stone embedded in the coatings and an elastic compound between the felt walls, substantially as described.
6. In an expansion joint, an elastic center of body material, means for confining said body material, means acting as a stay or

support for said body material, outer coatings and crushed stone or the like embedded 10 in said outer coatings.

ALEXANDER S. SPIEGEL.
